UNITED STATES PATENT OFFICE.

F. ROBERT SEIDENSTICKER, OF MERIDEN, CONNECTICUT, ASSIGNOR TO THE
BRADLEY & HUBBARD MANUFACTURING COMPANY, OF SAME PLACE.

DESIGN FOR AN ANDIRON.

SPECIFICATION forming part of Design No. 16,872, dated August 24, 1886.

Application filed July 19, 1886. Serial No. 208,509. Term of patent 7 years.

To all whom it may concern:

Be it known that I, F. ROBERT SEIDENSTICKER, of Meriden, in the county of New Haven and State of Connecticut, have invented 5 a new Design for Andirons; and I do hereby declare the following, when taken in connection with accompanying drawing, to be a full, clear, and exact description of the same, and which said drawing constitutes part of this 10 specification, and represents a perspective view.

This invention relates to a design for andirons; and it consists in the configuration and ornamentation as shown in the accompanying 15 illustration and hereinafter described. The upright divides at the base, the two sides curved outward and inward to form two scroll-like feet, and from the base the upright rises, gradually diminishing in width and forming 20 a continuation from the scroll-feet, the up-

rights terminating in a circular disk, on the face of which is the representation of an animal's head, as shown in the accompanying illustration.

I claim—

The herein-described design for andirons, consisting of the upright divided at the base and turned to the right and left, forming inwardly-turned scroll-like feet, the upright extending upward as a continuation from the 30 feet and gradually diminishing in width, terminating at the upper end in a circular disk, on the face of which is the representation of an animal's head, as shown in the accompanying illustration. 25

F. ROBERT SEIDENSTICKER.
